(57) **CLAIM**

The ornamental design for a flip bin organizer, as shown and described.

DESCRIPTION

FIG. 1 is a perspective view of the front side of our new design, showing the handle in an extended configuration. FIG. 2 is a front elevational thereof, showing the handle in a folded configuration.

FIG. 3 is a back elevational view thereof, showing the handle in a folded configuration.

FIG. 4 is a right side elevational view thereof.

FIG. 5 is a left side elevational view thereof.

FIG. 6 is a top side plan view thereof, showing the handle in a folded configuration; and,

FIG. 7 is a bottom side plan view thereof.

The broken lines illustrate portions of the flip bin organizer and form no part of the claimed design.
